DESIGN FOR AN AIR FINNED SMOKING PIPE

Wayne Leser, South Ozone Park, N. Y.

Application September 3, 1941, Serial No. 103,140

Term of patent 14 years

To all whom it may concern:

Be it known that I, Wayne Leser, a citizen of the United States, residing at South Ozone Park, Queens County, State of New York, have invented a new, original, and ornamental Design for an Air Finned Smoking Pipe, of which the following is a specification, reference being had to the accompanying drawing, forming part thereof.

Fig. 1 is a side elevational view of an air finned smoking pipe, showing my new design.

Fig. 2 is a top plan view.

Fig. 3 is an end view.

Fig. 4 is a bottom plan view of the same.

The characteristic features of my design reside in the portions shown in full lines on the drawing.

I claim:

The ornamental design for an air finned smoking pipe, substantially as shown and described.

WAYNE LESER.
